UNITED STATES PATENT OFFICE.

DAVENPORT LAWSON, OF ELK, CALIFORNIA, ASSIGNOR TO GOODYEAR REDWOOD CO.,
OF ELK, CALIFORNIA, A CORPORATION OF MAINE.

LEAD BLOCK.

Application filed January 27, 1921. Serial No. 440,295.

To all whom it may concern:

Be it known that I, DAVENPORT LAWSON, a citizen of the United States, and a resident of Elk, county of Mendocino, and State of California, have invented a new and useful Lead Block, of which the following is a specification.

My invention relates to sheave blocks and the broad purpose of my invention is to 10 provide an improved lead block for the lifting and control lines of my logging apparatus which is the subject of my copending application Serial Number 437,692, filed January 17, 1921 and patented October 25, 15 1921, No. 1,394,745. More particularly, an object of my invention is the provision of a block in which both lifting and control lines are handled without danger of tangling, and characterized by simplicity and strength 20 required in this service. Another object is the provision of a block of large size and great weight which may be assembled from relatively small and easily provided parts.

25 The invention possesses other objects and features of advantage, some of which, with the foregoing, will be set forth in the following description of the preferred form of my invention which is illustrated in the 30 drawings accompanying and forming part of the specification. It is to be understood that I do not limit myself to the showing made by the said drawings and description, as I may adopt variations of the preferred 35 form within the scope of my invention as set forth in the claims.

Referring to the drawings: Fig. 1 is a front elevation of the block and Fig. 2 is a side elevation.

40 The block of my invention comprises twin inside frame plates 2, each formed with a central boss 3, and laterally projecting arms 4. Stiffening webs 6 extending from the boss 3 are disposed on the frame and arms. 45 The twin plates are connected by a stiffening bar 7, preferably a section of pipe socketed in the bosses, and at their lower

ends by a foot yoke 8 pinned to each frame plate between the lugs 9 formed thereon by the bolts 11.

50 Arranged adjacent each frame plate 2 is an outside frame plate 12 similar to the inside plate and connected to it by the bolt 13 at the foot end which passes thru a spacing shell 14. At the head end, the frame plates are connected by the U-form bar 16 pinned to each by the bolts 17.

55 The bosses of each pair of inside and outside frame plates are formed with alined bearings in which a shaft 18 is journaled in bushing 19. Fixed on the shaft to turn between the frame plates is a sheave or pulley 21 grooved about its periphery to carry one of the lifting lines. A grease cup 22 fixed in each boss provides means for feeding lubricant to the shaft bearing. The outer bearing is closed by a cover plate 23, the 60 stiffening bar 7 acting as a closure for the inside bearings. In order to direct the lines into the block, an arcuate guide 24 is bolted 65 to each inside and outside frame, and extends around the upper half of the sheave. A head yoke 26 provided with apertures 27 for the attachment of the anchor lines, connects the U-bars of the twin frames, being pinned 70 thereto by bolts 28. The head yoke is also provided with apertures 29 for the convenient attachment of other lines.

75 Swung from the center of the foot yoke by a clevis 31 and U-bar 32 is a single frame, 80 mounting the sheave 33 over which runs the control line for the traveller carried by the lifting lines. The frame plates 34 of the single frame are duplicates and the same as the outside frame plates 12 of the twin 85 frames. The structures of sheave shaft, bearings and guides are also the same as those already described.

90 The block illustrated herein contains sheaves 16" in diameter mounted on hardened steel shafts 2½" in diameter. The service in which it is used involves supporting a double lifting line extending over a space as great as 5000 feet, together with a heavy

carrier and the carrier control lines and the log swung from the carrier.

I claim:

1. A block comprising twin frames, a sheave in each of said frames, means connecting said frames for holding them in fixed relation, a single frame pivotally suspended from said twin frames, and a sheave in said single frame.
- 5

2. A block comprising twin frames, a sheave in each of said frames, a head and a foot yoke connecting said frames, a single frame suspended from said foot yoke, and a sheave in said single frame.

In testimony whereof, I have hereunto set my hand.

DAVENPORT LAWSON.
